UNITED STATES PATENT OFFICE.

HJALMAR TORGERSSEN, OF EAGLE LAKE, MINNESOTA.

DESIGN FOR A BEAM GRUB-HOOK.

SPECIFICATION forming part of Design No. 33,958, dated January 22, 1901.

Application filed December 20, 1900. Serial No. 40,593. Term of patent 3½ years.

To all whom it may concern:

Be it known that I, HJALMAR TORGERSSEN, a citizen of the United States, residing at Eagle Lake township, in the county of Ottertail and 5 State of Minnesota, have invented and produced a new and original Design for Beam Grub-Hooks; and I do hereby declare the following to be a full, clear, and exact description of the same, reference being had to the accompanying drawing, forming a part thereof.

The figure is a perspective view of my new design.

As shown in the drawing, the leading or material feature of my design consists of a 15 beam having a curved hook terminating at one end in an inclined face and at the other end in an angle portion which offsets the hook out of the plane of the beam.

The beam 1 has an aperture 2 and is rectangular in shape to the portion 3, which forms 20 an obtuse angle pointing away from the side

of the beam. The beam has a hook 4, terminating at one end in the portion 3 and at the other end in points 5, having inclined faces 6. The hook is of semicircular shape, and the portion 3 offsets the hook out of the vertical and horizontal plane of the beam, and the points 5 stand under the offset portion 3 in the same vertical plane with the said portion, but out of the plane of the beam. 25

Having thus described my invention, what I claim as new, and desire to secure by Letters Patent, is—

The design for a beam grub-hook, substantially as herein shown and described. 30

In testimony whereof I affix my signature in presence of two witnesses. 35

HJALMAR TORGERSSEN.
